US0D1003653S

(12) **United States Design Patent** (10) **Patent No.:** **US D1,003,653 S**
(45) **Date of Patent:** **** Nov. 7, 2023**

(54) **USB ELECTRIC COFFEE GRINDER**

(71) Applicant: **Yiwu Siwei Technology Co., Ltd.,**
Zhejiang (CN)

(72) Inventor: **Changjiang Ding**, Zhejiang (CN)

(73) Assignee: **Yiwu Siwei Technology Co., Ltd.,**
Zhejiang (CN)

(**) Term: **15 Years**

(21) Appl. No.: **29/815,901**

(22) Filed: **Nov. 17, 2021**

(30) **Foreign Application Priority Data**

Sep. 6, 2021 (CN) 202130584980.5

(57) **CLAIM**

The ornamental design for a USB electric coffee grinder, as shown and described.

DESCRIPTION

FIG. 1 is a front, right, and top perspective view of a USB electric coffee grinder, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising a side wall.

The dot-dash broken lines depict the boundary of the enlarged views and form no part of the claimed design.

1 Claim, 9 Drawing Sheets
